LIQUID SPRAYER

Alec Bradley Kirkbride, Harrow-on-the-Hill, England,
assignor to Tudor Accessories Limited, London, Eng-
land

Filed June 1, 1970, Ser. No. 23,253

Claims priority, application Great Britain Dec. 17, 1969

Term of patent 7 years

Int. Cl. D23—01

U.S. Cl. D23—18

Fig. 1.

Fig. 2.

*Fig. 3.**Fig. 4.**Fig. 5.*FIG. 1 is a perspective view taken from the top front and one side of a liquid sprayer embodying my new design;

FIG. 2 is a perspective view taken from the bottom, front and side opposite that shown in FIG. 1;

FIG. 3 is a perspective view taken from one side thereof;

FIG. 4 is a top plan view thereof, with the hose and spray nozzle broken away for convenience of illustration; and

FIG. 5 is a cross-sectional view taken on line V—V of FIG. 3.

I claim:
The ornamental design of a liquid sprayer, substantially as shown.
